AIR COOLED ROTARY VALVE

Filed Oct. 25, 1923

Patented July 7, 1925.

1,545,205

UNITED STATES PATENT OFFICE.

JAMES SHAW, OF LODI, CALIFORNIA, ASSIGNOR TO H. S. MOTOR COMPANY, A COMMON-LAW TRUST OF ILLINOIS.

AIR-COOLED ROTARY VALVE.

Application filed October 25, 1923. Serial No. 670,762.

To all whom it may concern:

Be it known that I, JAMES SHAW, a citizen of the United States of America, residing at Lodi, in the county of San Joaquin and State of California, have invented certain new and useful Improvements in Air-Cooled Rotary Valves, of which the following is a specification.

This invention relates to means for cooling the rotary valves and associated parts of explosion engines, and more especially the type of such valves which form the subject matter of my prior Letters Patent No. 1,188,496, dated June 27th, 1916, and No. 1,292,103, dated January 21st, 1919, and the present improvements have as their object:—

To provide a structural formation and combination of engine parts, whereby cooling currents of atmospheric air are intermittently drawn through the hollow interiors of the valve and its casing, by the movement of the engine piston, to attain an effective cooling of said parts.

To provide a supplementary construction of parts whereby both the up and down strokes of the engine piston are utilized to attain the above mentioned cooling of the valve and valve casing, and in one part of the cycle of operation of the engine, utilize a portion of the air compressed in the crank casing as an auxiliary scavenging means for the combustion chamber, and at another part of such cycle of operation admit a portion of such air from the crank casing into the combustion chamber to add more air and effect a dilution of the uncompressed gaseous fuel charge in said chamber, all as will hereinafter more fully appear.

In the accompanying drawing:—

Fig. 1 is a vertical transverse section of an explosion engine having the present improvement applied.

Fig. 2, is a horizontal section on line 2—2 Fig. 1, of the rotary valve and its casing.

Fig. 3, is a detail section on line 3—3 Fig. 1, of the crank casing of a multicylinder engine of the present type. Like reference numerals indicate like parts in the different views.

In the drawing illustrative of the invention, the same is shown as adapted to a four cylinder engine, having a single hollow rotary valve 1 moving in a valve casing 2, common to the series of engine cylinders and controlling the operation of the same, as described in

detail in my aforesaid prior patents, and in the present improvement, the crank casing 3 of the engine will have separate chambers 4 individual to each engine unit and for the purpose hereinafter stated. 60

The rotary valve member 1 is of a hollow cylindrical form having diametrically arranged parts or passages 5 corresponding in number with the number of engine cylinders, and preferably having the progressive arrangement with relation to each other described in my prior patents aforesaid, with each of said passages 5 adapted to register the fuel inlet port 6 of an engine cylinder with the combustion chamber thereof, and in 70 the progressive rotation of said valve register said passage 5 with the outlet port 7 of the engine cylinder.

In the present improvement the end portions or trunnions of the valve 1 are formed 75 with central inlet passages 8 to connect the hollow interior of the valve with the outer air, while the midlength portion of the valve 1 is formed with ports or passages 9 communicating with the hereinafter described 80 air chamber of the casing 2 of the valve.

The valve casing 2, is of a hollow form similar to that in my aforesaid patents, with its annular chamber 10 adapted to communicate and receive air drawn through 85 the hollow valve 1, and to such end is formed with connecting ports 11 midway its length, as shown.

Each engine cylinder 12 is formed with an annular passage 13 in communication 90 with the lower end of the air chamber 10 of the valve casing 2, and adapted to receive air therefrom. At or near its lower end the chamber 13 communicates, in one form of the present improvement, with the 95 inlet end of a carburetor 14 of any usual type. In said form of the improvement, the outlet end of the carburetor is connected with the fuel inlet port or passage 6' of the valve casing 2 by a pipe or passage 15, so 100 that with a down stroke of an engine piston 16 in the cylinder 12 of the specified structure the external air, will be drawn through the hollow valve member 1 the hollow valve casing 2 and passage or chamber 13 of the 105 engine cylinder, thence through the carburetor 14, where the air is carburated, and thence into the combustion chamber of said engine cylinder. With such primary type 110 of the engine, the movement of outer air

through the parts, to cool the same, is of an intermittent nature, and with a view to a more continuous form in such flow of air, another part of the present improvement involves the utilization of the partial vacuum created in the closed crank casing 3 of the engine as an additional and intermediate means for aiding in the movement of air through the valve parts, and incidentally effect a more thorough scavenging operation in the combustion chamber of the engine.

To such ends the passage or chamber 13 in the walls of the engine cylinder, is connected to the interior or closed chamber 4 of the crank casing by a port or passage 17 at a point which is uncovered by the engine piston 16 at or near the end of its down stroke. In addition said chamber or passage 13 is connected to the crank case chamber 4 by a port or passage 18 at a point which is uncovered by the engine piston 16 at or near the end of its upstroke.

The operation is as follows:—

In the position of the engine parts shown in Fig. 1, the engine piston 16 is at the commencement of its down stroke to effect an introduction of fuel into the combustion chamber. In such movement of the piston, outer air is drawn through the interior of the hollow valve 1, the hollow valve casing 2 and wall chamber 13 of the engine cylinder, to exert a cooling action on the part, thence through the carburetor 14, to form a fuel charge, and from thence through the inlet ports 5, 6, and 6' into the combustion chamber of the engine.

As the engine piston 16 nears the end of its down stroke, the port or passage 17 in the cylinder wall is uncovered and any excess pressure of air in the closed chamber 4 of the crank casing 3, passes into the combustion chamber and add more air to the uncompRESSED charge of fuel therein.

In the succeeding upstroke of the engine piston 16, the same acts to create a partial vacuum in the closed crank casing 3, and as the piston nears the end of such upstroke the port 18 in the cylinder wall is uncovered. The partial vacuum existing in the crank casing 3, above set forth, acts to draw in a supply of outer air through the interior of the hollow valve 1, the hollow valve casing 2, and wall chamber 13 of the engine cylinder, into the crank casing until a balance of atmospheric pressure in said crank casing is attained. By such arrangement additional cooling effect on the engine parts is attained in another part of cycle of operation of the same, different from that above described.

In the succeeding upstroke of the engine piston 16, the fuel charge is compressed and fired, and in down stroke following, and as the piston nears the end of such down stroke, the port 17 in the cylinder wall is

uncovered, to admit air compressed in the crank casing 3, into the combustion chamber to aid in scavenging the same.

Having thus fully described my invention what I claim and desire to secure by Letters Patent, is:

1. In an explosion engine, the combination of a cylinder, a piston, a closed crank casing, a valve casing arranged at one end of the cylinder, and formed with an annular chamber, a revoluble valve member arranged in said valve casing and having a hollow interior open at an end and connected at a point remote from said open end with the annular chamber of the valve casing the valve and valve casing having registering fuel inlet passages, a carburetor having communication at one end with the annular chamber of the valve casing and at the other end with the fuel inlet passages of the valve and valve casing.

2. In an explosion engine, the combination of a cylinder, a piston, a closed crank casing, a valve casing arranged at one end of the cylinder and formed with an annular chamber, a revoluble valve member arranged in said valve casing and having a hollow interior open at its respective ends and connected at its midlength with the annular chamber of the valve casing the valve and valve casing having registering fuel inlet passages, a carburetor having communication at one end with the annular chamber of the valve casing and at the other end with the fuel inlet passage of the valve and valve casing.

3. In an explosion engine, the combination of a cylinder, a piston, a closed crank casing the cylinder having a passage in its wall and a port connecting said passage with the interior of the crank casing at a point uncovered by the engine piston at the end of its upstroke, a piston, a valve casing arranged at one end of the cylinder and formed with an annular chamber having communication with the passage in the wall of the cylinder, a revoluble valve member arranged in said valve casing and having a hollow interior open at an end and connected at a point remote from said open end with the annular chamber of the valve casing, the valve and the valve casing having registering fuel inlet passages, a carburetor connected at one end with the passage in the wall of the cylinder and at the other end with the fuel inlet passages of the valve and valve casing.

4. In an explosion engine, the combination of a cylinder, a piston, a closed crank casing the cylinder having a passage in its wall and a port connecting said passage with the interior of the crank casing at a point uncovered by the engine piston at the end of its upstroke, a piston, a valve casing arranged at one end of the cylinder and

formed with an annular chamber having communication with the passage in the wall of the cylinder, a revoluble valve member arranged in said valve casing and having a hollow interior open at its respective ends and connected at its midlength with the annular chamber of the valve casing, the valve and the valve casing having register-
ing fuel inlet passages, a carburetor connected at one end with the passage in the wall of the cylinder and at the other end with the fuel inlet passages of the valve and valve casing.

Signed at Lodi, California, this 17 day of October 1923.

JAMES SHAW.
